COMBUSTION AIR AND OIL VALVE

Filed Dec. 15, 1927

UNITED STATES PATENT OFFICE

CHARLES W. JOHNSON, OF SEATTLE, WASHINGTON

COMBINATION AIR AND OIL VALVE

Application filed December 15, 1927. Serial No. 240,255.

This invention relates to air and oil valves for oil burners such as are used for heating furnaces, and particularly to a mixing head having an air inlet and an oil inlet, and the general object of the present invention is to provide an oil valve which is normally closed but which will automatically open simultaneously with the inflow of air.

A further object is to provide a construction of this character wherein the oil valve is normally pressed against its seat by a spring but is provided with a lever and an impact member against which the air is projected, the projection of the air against this impact member acting to open the valve when the air is turned on.

My invention is illustrated in the accompanying drawing, wherein:—

Figure 1 is a schematic elevation of a furnace with my improved burner mechanism applied thereto;

Figure 2 is a longitudinal sectional view through the automatic air and oil valve which particularly constitutes the subject-matter of this application.

Referring to this drawing, and particularly to Figure 1, 10 designates the casing of the air and oil valve, which casing at one end is provided with the atomizing nozzle 11, this atomizing nozzle being of any suitable character but preferably rifled on its interior face so as to force out the mixed air and oil with a centrifugal whirl. This nozzle has screw-threaded engagement with the burner head or casing 10. The rear end of the burner head or casing is provided with the air inlet pipe 12 which is connected to an air compressor of any suitable character, designated 13 in Figure 1. Any other suitable source of air may be used, however.

The casing 10 is also provided with the oil inlet port formed with a seat 14 with which coacts a valve 15 illustrated as being conical in form and held to the seat by means of a spring 16. The oil line 17 is enlarged to form a valve casing 18 within which the valve 15 and its spring are disposed. The apex of the valve is connected to a lever 19 having the form of a bell crank lever. One arm of this lever is connected to the valve and the other

arm carries upon it a plate 20 which extends in front of or across the air inlet port 21 which is connected to the pipe 12.

Normally, and when the burner is not in use, the impact plate or baffle plate 20 extends across the end of the port 21, but when air is admitted or when the compressed air begins to flow due to the starting of the plant and this compressed air strikes the baffle plate or impact plate 20, it opens the oil valve, causing the air and oil to flow simultaneously into the burner head or casing 10. The forward end of this casing is tapered, as shown, so as to discharge the mixed air and oil into the nozzle 11 and so into the furnace. Preferably the air and oil valve and the burner head will be mounted as illustrated in my co-pending application, Serial #240,254 filed of even date herewith. It will be seen that the construction which I have devised provides an economical, safe, positive and leak-proof oil valve which is particularly desirable. The oil cannot flow unless the air is flowing and thus minimizes leakage and expense.

In Figure 1, I have illustrated the general connection of this air and oil valve in an oil burner plant, and in this figure A designates the furnace and B the fire door thereof. The burner head is preferably mounted in a hemispherical member C which is supported within the furnace for adjustment, as illustrated in the prior application above referred to. The air pipe 12 extends to an air compressor 13, previously referred to, while the oil pipe 17 extends to a gravity tank D. The oil is pumped into this tank by the oil pump E operated by the motor F, which is preferably an electric motor. The oil is pumped from any suitable reservoir or tank G. Valves H are provided in the oil and air line for controlling the flow and regulating the feed. Spark plugs are mounted within the burner head for the purpose of igniting the stream of mixed oil and air at any desired time.

While I have illustrated certain details of construction and arrangement of parts, I do not wish to be limited thereto, as obviously minor changes might be made therein without departing from the spirit of the invention as defined in the appended claims.

I claim:—

1. A burner head for oil burners, having an outlet opening at one end and at the other end having an air inlet opening, the side wall of the head being formed with a valve seat, an oil controlling valve coacting with said seat and resiliently urged to a seating position, an air valve hinged to the rear wall of the head and adapted to extend across the air inlet opening and having an angularly extended portion bearing against the inner end of the oil valve, whereby the air valve automatically causes the opening of the oil valve when the pressure of air is greater than the pressure urging the oil valve to its seat.
2. A burner head for oil burners having an air inlet port at one end and an outlet port at the other end and having an oil inlet port in its side wall, a rectilinearly movable valve operating in the oil inlet port and urged to its seat and having a portion extending through the oil inlet port, an air valve normally disposed to close the air inlet port and having an angular portion bearing against the inner end of the oil inlet valve, the oil inlet valve normally urging the air valve to its seat, the air valve under pressure of air behind it when said pressure is greater than the pressure urging the oil valve to its seat causing the opening of the oil valve.

In testimony whereof I hereunto affix my signature.

CHARLES W. JOHNSON.
